DEMOUNTABLE ARTILLERY-CARRIAGE

1,164,402.

Specification of Letters Patent. Patented Dec. 14, 1915.

Application filed February 3, 1914. Serial No. 816,229.

To all whom it may concern:

Be it known that I, FRIEDRICH SACHTLEBEN, residing at Essen-on-the-Ruhr, Germany, a subject of the Emperor of Germany, have invented a certain new and useful Improvement in Demountable Artillery-Carriages, of which the following is a specification.

This invention relates to demountable artillery carriages and particularly to those having a platform arranged for the placing of ammunition containers thereon. According to this invention these carriages are so constructed that their platforms, in order that they may be easily loaded upon pack animals, are demountable. Furthermore there are employed for the readily releasable connection of the platform parts, members which are themselves required in the construction of the carriage.

In the accompanying drawing forming part of this specification, in which one embodiment of the invention is shown by way of example, Figure 1 is a side view of the carriage loaded with ammunition containers, Fig. 2 is a top plan view of the same, partly in section with several of the ammunition containers omitted, and Fig. 3 is a section on the line 3—3 of Fig. 2 seen from the left.

The platform of the carriage is divided longitudinally of the carriage into halves A A¹, which will be suitably pressed from sheet metal and provided on their longitudinal sides as well as their ends, with upwardly presented flanges a² a³ a⁴. The inner longitudinal flanges a³ are, above, bent at right angles and lie with these deflected portions a⁵ in abutment. Upon the flanges a⁴ constituting the end walls of the parts A A¹ angle plates a⁶ (see specially Fig. 2) are secured. In the middle portion of the parts A A¹ are located cross pieces G G¹ (Figs. 1 and 2) of Π-shaped cross section and constructed of sheet metal which cross pieces, together with the angle plates a⁶ as well as the flanges a² and a³, constitute compartments for the ammunition containers B (Figs. 2 and 3). For securing the ammunition containers upon the carriage, straps D or the like serve.

Secured upon the inner flanges a³ of the platform parts A A¹, are holders C C¹ (Figs. 1 and 2) for the axle E of the wheels F. In these holders which project into the cross

pieces G G¹, the wheel axle E rests without play, and it projects with play into openings a⁷ of the outer flanges a² of the platform parts. A locking bolt c² or the like introduced through the holder C and the wheel axle E secures the wheel axle against turning and longitudinal displacement. To enable the introduction of the locking bolt c², an opening g² (Fig. 2) is provided in the web G of one of the cross pieces G G¹.

Near each end of the flanges a³ of the platform part A is located an eye H which overlaps with and preferably fits between two eyes K K¹ secured to the flange a³ of the part A¹. The eyes H, K, K¹, constitute the bearings for the pins m¹ and n¹ of the thill M and a limber-hook N so that by means of these pins and the eyes H, K, K¹, the platform parts A and A¹ are connected together in an easily detachable manner. The pins m¹ and n¹ are secured against turning as well as longitudinal displacement within their bearings, through the medium of check pins P. These check pins are readily accessible in consequence of the arrangement of recesses a⁸ in the flanges a³.

For demounting the carriage the wheels F are first removed from the wheel axle E, whereupon the wheel axle is withdrawn from the holders C C¹ and the platform flanges a², and the pins of the thill M and of the limber-hook N are withdrawn from the eyes H, K, K¹. The platform parts can now be separated from each other and so loaded upon the saddle of a pack animal that the same weight hangs on each side. After separation of the platform, the limber-hook N is again attached to its pair of eyes K K¹.

I claim:

1. A demountable artillery carriage having a platform constructed to receive ammunition containers and having a limber-hook and a draft member provided with means for attaching them to the carriage; said platform being divided longitudinally of the carriage into platform parts and said platform parts being connected to each other in an easily detachable manner by the attaching means of the limber-hook and draft member.

2. A demountable artillery carriage having a platform arranged to receive ammunition containers and having a limber-hook and a draft member with attaching pins for

connecting them to the carriage, said platform being divided longitudinally of the carriage into two parts and said platform parts having overlapping eyes which receive the pins of the limber hook and the draft member and thereby connect the platform parts together in an easily detachable manner.

3. A demountable artillery carriage having a platform divided longitudinally of the vehicle into two parts; said platform parts having overlapping eyes, members fitted to said overlapping eyes for securing said platform parts together in an easily detachable manner, said members forming traction organs for the carriage.

4. A demountable artillery carriage having a platform divided longitudinally of the carriage into two parts and having said parts provided with means for releasably securing them to the wheel axle; said platform parts being constructed to overlap each other and said carriage having a limber-hook and a thill coupling, each adapted to extend through overlapped portions of the platform parts to secure said platform parts together in an easily detachable manner.

5. A demountable artillery carriage having wheels, an axle for said wheels and a platform embodying in its construction, flanges, angle plates and cross pieces, and thereby adapted to receive ammunition containers; said carriage also having a limber-hook and a draft member provided with means for attaching them to the carriage; said platform being divided longitudinally of the carriage into two parts; and said platform parts being connected to each other in an easily detachable manner by the attaching means of the limber-hook and draft member; holders for said wheel axle, said holders being secured upon said platform parts in the vicinity of the joint between said platform parts, a locking bolt introduced through one of said holders and the wheel axle, an opening in one of said cross pieces to enable the introduction of said locking bolt.

The foregoing specification signed at Barmen, Germany, this 15th day of January, 1914.

FRIEDRICH SACHTLEBEN. [L. S.]
